MIXER CABINET

William E. Dunn, Westwood, Colo.

Application September 4, 1948, Serial No. 47,881

3 Claims. (Cl. 312—23)

1

This invention relates to prefabricated housing or cabinet units of a general type commonly employed in multiple arrangements as kitchen, pantry, and like facilities, and more particularly to such units particularly adapted to house and operatively support electric mixers and similar equipment units in a manner susceptible of integration with other conventional cabinets, and has as an object to provide an improved such cabinet unit.

A further object of the invention is to provide an improved construction and arrangement of elements constituting a cabinet for the housing and operative support of an electric mixer.

A further object of the invention is to provide an improved cabinet characterized by an altitudinally-reciprocable mounting platform automatically responsive to manipulation of a cabinet hinged end closure.

A further object of the invention is to provide an improved cabinet susceptible of convenient manipulation to house and enclose an electric mixer within its upper portion and to alternatively position and operatively support said mixer in readily-accessible projection thereabove.

A further object of the invention is to provide improved means for operatively interrelating an altitudinally-reciprocable platform and a hinged end closure in a cabinet to automatically reflect articulation of said cover as corresponding, proportional adjustment of said platform.

A further object of the invention is to provide an improved cabinet for the housing and operative support of an electric mixer that is simple and relatively inexpensive of manufacture, susceptible of production in a wide range of particular sizes, proportions, materials, and finishes, that is adaptable to use either as an independent unit or in assembled correlation with other cabinet units, that is positive and efficient in operation, long-lived in use, and characterized by marked utilitarian advantage.

With the foregoing and other objects in view, my invention consists in the construction, arrangement, and combination of elements herein-after set forth, pointed out in my claims, and illustrated by the accompanying drawings, in which—

Figure 1 is a vertical section taken through a typical embodiment of the invention in closed, mixer-housing relation of its movable elements. Figure 2 is a front elevation of the construction shown in Figure 1 as opened to position and operatively support the mixer ready for use, certain portions of the view being broken away to

disclose otherwise concealed construction. Figure 3 is a fragmentary, detail section, on an enlarged scale, taken substantially on the indicated line 3—3 of Figure 2 with the cover and platform 5 of the unit in intermediate positions of their actuation range. Figure 4 is a fragmentary, detail, bottom plan view, partly in section, of automatic latch means operatively associated with the movable platform of the unit. Figure 5 is a fragmentary, detail section taken substantially on the indicated line 5—5 of Figure 4. Figure 6 is a view similar to Figure 3 illustrating a somewhat modified, alternative construction of the elements interengaging the unit cover and platform. Figure 7 is a section, similar to Figure 1, through an alternative, modified unit construction embodying the principles of the invention, the electric mixer being omitted. Figure 8 is a front elevation, partly in section, of the construction according to Figure 7 as opened and extended for operative positioning of a mixer. Figure 9 is a fragmentary, detail section, on an enlarged scale, taken substantially on the indicated line 9—9 of Figure 7 with the movable elements of the unit in an intermediate position of their actuation range.

Electric mixers are in common and wide-spread use in a variety of particular makes and constructions, such appliances requiring storage space when not in use and an operative base or position to which they may be transferred for practical employment. Together with the advent of electric mixers, it has become a general practice to supply prefabricated cabinet units in a variety of sizes, arrangements, and proportions susceptible of interrelation to constitute counters, tables, and the like, adapted to function as kitchen and pantry facilities with marked conservation of space. Given the problem of electric mixer storage and operative positioning and the availability of multiunit cabinet installations, it is desirable and wholly feasible to provide a cabinet unit particularly arranged to house and operatively support a mixer appliance with conservation of space and enhanced convenience, and the instant invention is directed to such end.

In the construction of the embodiment of the invention represented by Figures 1—5, inclusive, a rectangular cabinet unit of any desired size, material, and particular proportions is shown as a hollow assembly, open at its upper end, comprised from rigidly interrelated side walls 10, front wall 11, rear wall 12, and bottom 13. A base 14 may be provided in inwardly-offset relation with the front wall 11 to elevate the bottom 13 somewhat above the surface supporting the cabinet, as

is common practice, and a cover 15 is hinged at one of its margins to the rear wall 12 in position to engage and close over upper margins of the walls 10 and 11, at times, and to be swung upwardly out of engagement with said wall 10 and 11 margins and into substantially coplanar relation with wall 12 to fully open and expose the cabinet unit upper end, at other times, as is also conventional practice in the construction of cabinets of various types. Since, in accordance with the concept of the invention, only an upper portion of the cabinet interior is utilized for storage of the electric mixer, an access opening closable by a hinged door 16 is formed through the lower portion of the front wall 11, and the interior of the cabinet served by said access opening may be furnished with transverse partitions or shelves 17, in any convenient or desired arrangement, adapting the cabinet lower interior for storage uses.

A rigid platform 18 is sized to fit transversely within, to substantially fill, and to reciprocate altitudinally of the cabinet upper portion defined by the walls 10, 11 and 12, said platform being preferably furnished with guide arms or blocks 19 fixedly depending therefrom adjacent and for sliding engagement with inner surfaces of the walls 11 and 12, whereby tilting of said platform 18 out of a position substantially perpendicular to the walls 11 and 12 is inhibited. The platform 18 serves as a mounting and support for an electric mixer 20, of any desired make or construction, whereof the base may rest upon or be secured to the upper platform surface in any desired or convenient relation.

The invention contemplates that the platform 18 carrying the mixer 20 shall react altitudinally to opening and closing of the cabinet end cover 15 for retraction of the mixer wholly within the cabinet upper end when said cover is closed and for elevation of said mixer into projected relation above the cabinet upper end when said cover is opened, the platform 18 registering with the upper end of the cabinet to position the mixer for use. To give effect to the contemplation of the invention, an L-shaped fitting 21 is secured to and depends below each side of the platform 18 with one of its legs inwardly paralleling the adjacent side wall 10, said fittings 21 being spaced along the platform side margins like distances forwardly from the cabinet rear wall 12, and a bracket arm 22 is secured to the inner surface of the cover 15 adjacent each side thereof to depend adjacent and parallel to the cabinet side wall 11 inner surfaces when said cover is closed relative to the cabinet, said arms 22 hence lying in approximately the same planes as the vertical legs of the respective fittings 21 and being movable with the cover 15. A link 23 hingedly connects between the free end of each bracket 22 and the vertical web of the fitting 21 on the same side of the platform 18, clearance for said links 23 being provided between side margins of the platform and the adjacent cabinet side walls, and the lengths of the so-related brackets 22 and links 23 are proportioned and correlated to lower the platform interiorly of the cabinet a distance sufficient for accommodation of the mixer 20 between said platform and the cover 15 when the latter is closed, and to elevate said platform into approximate registration with the cabinet open end when the cover 15 is swung into substantially coplanar relation with the cabinet rear wall 12, it being obvious that the location of the fitting 21 along the platform side margins, the particular

shape and length of the bracket 22 and location of said bracket relative to the hinge axis of the cover 15, as well as the link 23, are all susceptible of variation and adjustment to provide the desired range of platform 18 altitudinal travel.

To minimize the effort necessary for elevation of the platform 18 and its mixer 20 through manipulation of the cover 15, the weight of said platform and mixer is largely counterbalanced through any practical arrangement of means effective for such purpose, one such arrangement being illustrated as comprising a lever arm 24 hinged at one of its ends to each of the side walls 10 below the lowermost travel limit of the platform 18 and to swing through a vertical arc paralleling the side wall to which it is attached. A link 25, suitably proportioned in length, hingedly engages between the fitting 21 and an intermediate point of the associated arm 24, and a retractile coil spring 26 operatively connects between the free end of the arm 24 and a point on the link 25 adjacent its connection with the fitting 21, said spring 26 hence constituting the hypotenuse of a triangle whereof the legs are the link 25 and the end of the arm 24 beyond said link on the side of the latter remote from the arm attachment to the wall 10, said hypotenuse increasing in length as the arm 24 and link 25 are relatively actuated as a consequence of platform 18 descent, thereby elongating the spring 26, and shortening with consequent contraction of said spring as the platform approaches its uppermost position, thereby proportioning the counterbalancing effect of the spring tension to the otherwise unbalanced load imposed by the cover 15, platform 18 and mixer 20.

A latch automatically engageable when the platform 18 is in its uppermost position to secure said platform against non-intentional retraction within the cabinet is provided in the form of a bar 27 pivoted at its center to the under side of the platform 18 beneath the approximate center line of the latter in perpendicularly-bridging relation between the cabinet walls 11 and 12, said bar 27 preferably engaging through elongate loop guides 28 carried by the platform under surface adjacent the bar ends to limit oscillation of said bar about its pivot in either direction of its movement. An expansive coil spring 29 acts between one side of the bar 27 and an abutment lug 30 fixed to the platform 18 under surface in laterally-spaced relation with said bar to normally and yieldably hold said bar at one limit of its oscillatory range, and latch plates 31 are fixed to inner surfaces and adjacent the upper ends of the cabinet walls 11 and 12 for engagement by ends of the bar 27 projecting beyond the platform 18 margins when said platform is elevated to registration with the cabinet upper end. The latch plates 31 are formed with notches opening in their upper margins engageable by the bar 27 ends in the normal, spring-positioned disposition of said bar, and laterally-directed margins of said plates 31 are oppositely inclined or beveled downwardly and away from the path of bar 27 upward travel for engagement with the margins of the bar ends as the latter ascend with the platform 18, said latch plate inclined margins operating to swing the latch bar ends against the pressure of the spring 29 as the platform approaches its upper limit, said latch bar being free to react to the pressure of its spring for engagement of its ends in the latch plate notches when said bar ends have cleared the uppermost points 75 of the latch plate margins. The end of the latch

bar 27 adjacent the cabinet front wall 11 is formed as or furnished with an actuating finger 32 fixedly upstanding therefrom past the forward margin of the platform 18, said finger 32 providing means for manual shift of the latch bar 27 against the pressure of its spring 29 and release of its engagement with the latch plate 31 notches when it is desired to close the cover 15 and retract the platform 18 and mixer 20 within the cabinet.

To avoid complications resulting from intrusion of the counterbalance or other mechanisms within the storage space of the cabinet lower interior, side panels 33 may be fixed to bridge between lower portions of the cabinet walls 11 and 12 in inwardly-spaced parallelism with the adjacent side walls 10, thereby to form upwardly-opening pockets along said side walls for the reception of the actuating mechanism, and the storage shelves 17 may in such case engage with and close between said panels 33; it being convenient in such an arrangement to notch upper corners of the panels 33 adjacent the walls 11 and 12 for seated reception of the fingers 19 when the platform 18 is at its inner, or lowermost, position.

The alternative construction illustrated by Figure 6 is in all essential operative respects the equivalent of that shown in the preceding figures and hereinabove described, the only difference presented by the embodiment of Figure 6 being structural in an actuating arrangement permitting the use of a relatively much shorter member in substitution for the bracket 22 secured to the cover 15. As shown in Figure 6, a relatively quite short bracket 34 is fixed to the cover 15 under surface more closely adjacent the hinge axis of said cover than the bracket 22, and a link 35 hingedly connects with and depends from the free end of the bracket 34 between platform 18 side margins and the adjacent cabinet walls 10 to hinged connection at its lower end with an intermediate point of a lever arm 36 hingedly projecting from the cabinet rear wall 12 below the platform 18 lowermost position for actuation in a vertical arc along the adjacent cabinet side wall 10; the link 23 hingedly depending from the fitting 21 to hinged connection of its free end with the corresponding free end of the arm 36, so that said latter arm operates as a lever of the third class to elevate or retract the platform 18 through the agency of the link 23 as the link 35 is actuated to less degree through the displacement of the short bracket 34 consequent upon articulation of the cover 15 about its hinge axis.

Figures 7, 8 and 9 typify an alternative construction and arrangement of elements adapted to give effect to the principles of the invention in association with a relatively narrow cabinet having its cover 15 hinged to the upper margin of one of the side walls 10 for actuation between perpendicular and coplanar relation with said side wall; narrow cabinets of the type illustrated being practical for association with other cabinet units of like height and depth, while the side-hinging cover 15 requires a rearrangement of the elements for actuating the platform 18 in order to eliminate obstruction of the platform forward margin and access to the platform-supported mixer when the cover 15 is open.

In the alternative construction, a rigid yoke 37, generally U-shaped in plan, is hinged at its base by means of fittings 38 to and transversely of the cabinet rear wall beneath the lowermost position of the platform 18 to dispose its generally parallel arms 37' for actuation in vertical arcs inward-

ly paralleling the cabinet side walls 10 beneath said platform. The yoke arms 37' extend forwardly within the cabinet to hinged engagement of their forward ends with the lower ends of links 23 hingedly depending from the platform fittings 21, so that oscillation of the yoke 37 base in its fittings 38 is reflected as altitudinal adjustment of the platform 18 interiorly of the cabinet. Linking the yoke 37 to and for reaction to manipulation of the cover 15, a relatively-short bracket 34 is secured adjacent a rear margin of the cover 15 to project perpendicularly from the under surface of said cover in a minimum spacing from the cover hinge axis, and an arm 39 is hinged at its upper end to said bracket and depends therefrom between the cover-mounting side wall 10 and adjacent margin of platform 18 downwardly past the adjacent yoke arm 37', and a link 40 hingedly connects the lower end of said arm 39 with a point on the adjacent yoke arm 37' spaced forwardly of the cabinet from the hingedly-mounted yoke base, the linkages and connections above described being proportioned in an obvious manner to accomplish the desired travel of the platform 18 in response to opening and closing of the cabinet cover 15. As is indicated in the drawings, the alternative construction just above described is adapted for operative association with counterbalancing means of the type and construction illustrated in the preceding views and hereinabove explained.

In any of the illustrated embodiments, or in other analogous constructions, the improvement provides a useful and highly adaptable facility for the storage and operative support of electric mixers and comparable appliances in a manner conservative of space and user energy; the cabinet cover 15 completing a secure protective housing for the appliance when closed to provide a smooth, horizontal working area available for many purposes, the latch bar positively and securely positioning the platform and its supported appliances in position for use of the latter, and the upright disposition of the opened cover 15 introducing a minimum of interference when the appliance is positioned for use.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. In a mixer cabinet having an open-top housing defining a straight-walled well in its upper portion and a cover hinged to said housing for actuation through a vertical arc between opening and closing relation with the housing top, a platform laterally of and reciprocable altitudinally within said well, connections between said cover and platform operable as an incident of cover actuation to elevate the platform to the housing top when the cover is fully open and to depress the platform within the housing well in spaced parallelism with the cover when the latter is closed, and selectively-releasable means automatically operable as an incident of platform upward travel to latch said platform in its uppermost position, means for counterbalancing the weight of said platform and its load operatively engaging between said housing and platform, said means comprising like arms similarly hinged to inner faces of opposed housing walls beneath the plat-

form lowermost position for actuation in vertical arcs paralleling said faces, like links hingedly depending from platform side margins above said arms to hinged connection of their lower ends with points of the corresponding arms spaced inwardly from the arm free ends, and a retractile spring operatively between each arm free end and the end of the associated link adjacent the platform.

2. In a mixer cabinet having an open-top housing defining a straight-walled well in its upper portion and a cover hinged to said housing for actuation through a vertical arc between opening and closing relation with the housing top, a platform laterally of and reciprocable altitudinally within said well, means for counterbalancing the weight of said platform and its load operatively engaging between said housing and platform, and selectively-releasable means automatically operable as an incident of platform upward travel to latch said platform in its uppermost position, connections between said cover and platform operable as an incident of cover actuation to elevate the platform to the housing top when the cover is fully open and to depress the platform within the housing well in spaced parallelism with the cover when the latter is closed, said connections comprising a single, relatively-short bracket fixedly projecting perpendicularly from the cover inner face near the cover hinge axis and adjacent one of the cover side margins for free oscillation through the top of the housing well, a U-shaped yoke hinged at its base to one of the housing side walls below the platform lowermost position for actuation of its arms through vertical arcs underlying the platform margins paralleling the cover hinge axis and about an axis perpendicular to that of the cover hinge, links hingedly connecting the yoke arm free ends with intermediate points of the overhanging platform margins, a link hingedly depending from the free end of said bracket past and below the adjacent yoke arm, and a link hingedly connecting the lower end of the bracket-engaged link with a point on the adjacent yoke arm spacedly adjacent the yoke hinge axis.

3. In a mixer cabinet having an open-top housing defining a straight-walled well in its upper

portion and a cover hinged to said housing for actuation through a vertical arc between opening and closing relation with the housing top, a platform laterally of and reciprocable altitudinally within said well, means for counterbalancing the weight of said platform and its load operatively engaging between said housing and platform, and connections between said cover and platform operable as an incident of cover actuation to elevate the platform to the housing top when the cover is fully open and to depress the platform within the housing well in spaced parallelism with the cover when the latter is closed, selectively-releasable means automatically operable as an incident of platform upward travel to latch said platform in its uppermost position, said means comprising a latch bar perpendicularly traversing and pivoted at its center to the under face of said platform in end projection beyond the intersected platform margins, stops limiting oscillation of said bar about its pivot in one direction, a spring yieldably urging said bar to the oscillatory limit determined by said stops, notched plates fixed adjacent the housing wall inner face tops in the reciprocatory path of the bar end projections, inclined margins on said plates engageable with the bar end projections during platform upward travel to oscillate said bar about its pivot against the pressure of said spring, said inclined margins leading to the notch openings of said plates, and an actuating finger upstanding from one of the bar end projections across and beyond the platform margin remote from the cover hinge axis.
